CLAIM

The ornamental design for a portable fluid dispenser, as shown and described.

DESCRIPTION

FIG. 1 is a front perspective view of a portable fluid dispenser showing my new design;

FIG. 2 is a rear perspective view thereof;

FIG. 3 is a top plan view thereof;

FIG. 4 is a front elevational view thereof;

FIG. 5 is a rear elevational view thereof;

FIG. 6 is a side elevational view, as viewed from the left in FIG. 1;

FIG. 7 is a side elevational view thereof, as viewed from the right in FIG. 1; and

FIG. 8 is a bottom plan view thereof.

The broken lines shown in FIG. 1 of a water container are for illustrative purposes only and form no part of the claimed design.

Fig. 1.

Fig. 2.

Fig. 3.

Fig. 8.

Fig. 4.

Fig. 5.

Fig. 6.

Fig. 7.
